Attorney

UNITED STATES PATENT OFFICE.

BENJAMIN F. ADAMS, OF STRATFORD, TEXAS.

PIPE-WRENCH.

1,184,061.

Specification of Letters Patent. Patented May 23, 1916.

Application filed November 17, 1915. Serial No. 61,956.

To all whom it may concern:

Be it known that I, BENJAMIN F. ADAMS, a citizen of the United States, residing at Stratford, in the county of Sherman and State of Texas, have invented certain new and useful Improvements in Pipe-Wrenches, of which the following is a specification, reference being had to the accompanying drawings.

10 My invention relates to wrenches, and particularly to the type of wrench illustrated in my prior Patent No. 1,095,616, granted to me May 5, 1914, the particular object of the invention being to improve 15 upon my prior patent by the provision of means whereby the movable jaw shall be adjustable along the length of the wrench shank so as to thereby adjust the device to different sizes of work.

20 A further object of the invention is to improve upon the construction illustrated in my prior patent by providing means whereby it may be adjusted quickly.

Other objects will appear in the course of 25 the following description.

My invention is illustrated in the accompanying drawings, wherein:

Figure 1 is an elevation of my improved wrench, some of the parts being in section; 30 Fig. 2 is a top plan view; Fig. 3 is a perspective view of the movable jaw; Fig. 4 is a perspective view of the spring; Fig. 5 is a perspective view of the latch.

Referring to these figures, 10 designates 35 the handle of a wrench which at one end is formed to provide the hook-shaped jaw 11, the inner face of which is provided with teeth 12. This shank is longitudinally slotted, as at 13, and upon one edge of the 40 shank is provided with the ratchet teeth 14.

Pivottally mounted upon the shank is a movable jaw designated generally 15. This jaw is transversely U-shaped in configuration and embraces the shank 10 and is held 45 to the shank by a pivot bolt 16 which passes through the slot 13. The extremity of the jaw is curved and formed with teeth 17 co-acting with the teeth of the fixed jaw. Also pivottally mounted upon the pivot bolt 16 is 50 a latch member illustrated in detail in Fig. 5 and designated generally 18. This latch member comprises a body or solid portion 19 having laterally disposed arms 20 and laterally disposed arms 21 extending at 55 right angles to the arms 20. The arms 20

are laterally offset at their extremities so that they can pass over the rearwardly ex- with the bolt 16.

Slidably mounted upon the shank 10 is a spring 22. This spring extends approxi- 60 mately parallel to the shank and at one extremity is formed with the T-shaped head 23. The opposite end of the spring is angularly bent and formed with a collar 24 which embraces the shank 10 and is 65 movable therealong. The shank 10 is formed with outwardly projecting ears 25 and a pin 26 extends across these ears and bears frictionally against the spring 22. This provides for shifting the spring in accord- 70 ance with the adjustment of the movable jaw. The pressure on the movable jaw when the wrench is being used causes the spring 22 to bind against the pin 26 and upon the shank 10 so as to hold the spring 75 in its adjusted position. But when the wrench is not in use the spring may be readily shifted by hand along the extent of the shank. As will be noted from Fig. 1, the portion 19 or body of the latch 18 80 is formed to provide a tooth 27 which is engageable with any one of the notches or teeth 14, so as to hold the latch in its adjusted position.

In the practical use of my invention the 85 latch 18 is released from its engagement with the teeth 14 and shifted longitudinally, which will shift the movable jaw toward or from the fixed jaw. The latch is then reengaged with the corresponding notch or 90 tooth 14 and the fixed jaw is held from further movement. At the same time the spring 22 is caused to longitudinally slide so as to bring the spring in proper position with relation to the movable jaw. This 95 improvement renders my wrench readily adjustable to various sizes of work and this adjustment is very simple and may be very quickly made. I have found it extremely effective in practice, and furthermore, the 100 wrench may be cheaply made and sold.

Having described the invention, what I claim is:

1. A wrench of the character described including a shank having a fixed jaw and being longitudinally slotted, a jaw having a pivot member passing through the slot of the shank whereby the jaw is rendered longitudinally adjustable along the shank, means connected with the pivot of the mov- 110

able jaw for holding it in adjusted position but permitting free movement of the jaw on its pivot, and a spring bearing against the movable jaw and urging it toward the shank.

5 2. A wrench of the character described including a shank having a fixed jaw and being longitudinally slotted, a jaw having a pivot member passing through the slot of the shank whereby the jaw is rendered longitudinally adjustable along the shank, means connected with the pivot of the movable jaw for holding it in adjusted position but permitting free movement of the jaw on its pivot, and a spring bearing against 10 the movable jaw and urging it toward the shank.

15 3. A wrench of the character described including a shank having at one end a fixed jaw and being longitudinally slotted, a pivot pin passing through the slot of the shank, a movable jaw pivotally mounted upon said pivot pin and thereby mounted for oscillation and longitudinal adjustment, a latch mounted upon the pivot pin and operatively 20 engaging with the shank to hold the pivot pin in adjusted position, and a spring longitudinally adjustable upon the shank and 25

having its free end engaging with the said movable jaw to urge it toward the shank.

4. A wrench of the character described including a shank longitudinally slotted intermediate its ends and having a fixed jaw formed thereon at one end, a bifurcated movable jaw embracing the shank, a pivot pin passing through said jaw and through the slot, a latching member having arms at one end embracing the shank and the pivotal end of the movable jaw and connected to the pivot thereof, the other end of the latch member being bifurcated to embrace the shank, a tooth formed upon said latch member, the shank being formed with teeth with which said latching tooth is adapted to engage to hold the movable jaw in adjusted position, and a longitudinally adjustable spring mounted upon the shank and having its free end engaging with said movable jaw to urge it toward the shank. 30 35 40

45 In testimony whereof I hereunto affix my signature in the presence of two witnesses.

50 BENJAMIN F. ADAMS.
